LIGHTING FIXTURE

Theophile A. Stiffel, Chicago, Ill.

Application February 21, 1957, Serial No. 44,933

Term of patent 7 years

(Cl. D48—19)

I claim:

The ornamental design for a lighting fixture, as shown.
